CONVERSION OF HYDROCARBONS

Homer Z. Martin, Cranford, Harvey E. W. Burnside, Locust, and Frank T. Barr, Summit, N. J., and Robert W. Krebs, Baton Rouge, La., assignors to Esso Research and Engineering Company, a corporation of Delaware

Application May 27, 1953, Serial No. 357,752

3 Claims. (Cl. 196—55)

This invention relates to a process for treating hydrocarbons and more particularly relates to the cracking or coking of heavy residual oils to produce lower boiling hydrocarbons and coke.

The hydrocarbon residual oil which is to be cracked according to the present process is a high boiling hydrocarbon oil which cannot be vaporized at ordinary pressures without cracking the high boiling constituents. The residual oil may be that produced by distilling crude petroleum oil at ordinary atmospheric pressure or under subatmospheric pressure such as vacuum distillation. The present process may also be used for cracking or coking shale oils, pitches, tars, etc.

Processes are known in the prior art for cracking or coking residual oils in the presence of finely divided inert or substantially inert solids maintained as a fluidized bed.

In the present process a dense fluidized bed of finely divided inert solids such as sand, coke, etc. is used and the preheated residual oil is introduced into the dense fluidized bed of finely divided solids maintained at reaction temperature. Vaporous products of coking are taken overhead and further treated as desired to recover lower boiling hydrocarbon fractions. During coking more coke is formed and some coke may be withdrawn from the process as product coke. Coke particles from the coking zone or reactor are stripped to remove volatile hydrocarbons therefrom. Some of the stripped coke particles may be withdrawn as product coke and the rest of the coke particles are passed to a burner where they are preferably maintained in a dense fluidized condition and contacted with air or other oxygen-containing gas to burn some of the coke particles and to supply heat to the coke particles. Or a transfer line burner may be used in which the superficial gas velocity is between about 10 and 60 feet per second. The heated coke particles are then returned to the coking zone to supply heat thereto.

One of the problems in the fluid coking of residual or other heavy oil feeds is the deposition of coke in the overhead system, that is, in that part of the process where hot products of coking leave the coking zone or after they leave the coking zone. The hot products of coking leaving the dense fluidized bed in the reactor contain entrained coke particles and most of these particles are removed by passing the products of coking through a device such as a cyclone separator or the like for separating solid particles from the hot products of coking. One or more stages of cyclone separators may be used and they may be arranged inside the coking zone at the top thereof or outside the coking zone. Deposition of coke occurs in the cyclone separator and causes the pressure drop through the cyclone separator to build up to such an extent that the coking unit has to be shut down for cleaning due to this cause. Deposition of coke also occurs in the lines leading to and from the cyclone separator.

The problem of coke deposition is avoided in the

present process by injecting or introducing hot adsorbent finely divided solid particles into the cyclone separator inlet when the cyclone separator is located within the coking zone. If the cyclone separator is located outside the coking zone it is preferred to introduce the hot adsorbent particles into the outlet of the coking zone leading to the cyclone separator. In some cases it may also be desirable to introduce hot adsorbent finely divided particles into the outlet line from the cyclone separator at one or more spaced points to maintain the products of coking at coking temperature or higher.

The hot adsorbent particles to be used comprise hot coke particles withdrawn as a separate stream or streams from the burning zone. In some cases it may be desirable to increase the surface area of the coke particles to be used as the hot adsorbent particles and this is preferably done by treating the particles with steam at high temperatures.

In the drawing the figure represents one form of apparatus adapted for carrying out the process of the present invention.

Referring now to the drawing, the reference character 10 designates a reactor or coking zone containing a fluidized dense bed 12 of solid finely divided inert particles such as coke or the like. The dense bed 12 has a level indicated at 14 with a dilute or disperse phase 16 thereabove. The inert solids of the fluidized bed 12 have a particle size between about 20 and 1000 microns preferably between about 50 and 400 microns and may comprise petroleum coke, or other coke, coke formed in the process, spent cracking catalysts, pumice, Carborundum, alumina or other materials refractory under the operation conditions.

The fluidized bed 12 is maintained at a temperature between about 800° and 1600° F. When coking to produce motor fuel such as gasoline, temperatures in the lower range of about 800° to about 1200° F., preferably about 900° to 1100° F. will be used whereas when coking at extremely high temperatures to produce chemicals such as unsaturated hydrocarbon gases and aromatic hydrocarbons, temperatures in the higher range of about 1200° to about 1600° F., preferably about 1250° to 1450° F. will be used.

The oil feed to be converted is introduced into the dense fluidized highly turbulent bed 12 in the reactor via feed line 18 provided with nozzles 22 for distributing the oil feed on the hot inert solids. In some cases it may be desirable to feed or spray the oil feed into the dilute phase 16 above the dense bed level 14. The oil feed is preferably preheated in any suitable manner to a temperature between about 600° and 800° F. before being introduced into the reactor 10. The preheating is done to reduce the low temperature viscosity of the oil and render it fluid. The oil feed may be high boiling hydrocarbon oils, comprising a residual petroleum oil such as tar, pitch, crude residuum, heavy bottoms or other similar stock having a gravity between about 10° and 20° API, a Conradson carbon between about 5 and 50 wt. % and an initial boiling point between about 850° and 1200° F. Steam may be introduced at one or more points 24 to assist in maintaining the bed in fluidized condition or steam may be added with the oil feed in line 18.

The fluidized bed 12 is maintained as such by the upflowing hydrocarbon gases and vapors formed by the coking of the oil feed and by the steam added to the process. The superficial velocity of the gases and vapors passing upwardly through the bed 12 is between about 0.5 and 4 feet per second when using finely divided coke of about 50 to 400 microns, and at a superficial velocity of about 1 to 2 feet per second, the density of the fluidized bed will be about 40 lbs. per cu. ft. but

may vary between about 15 and 60 lbs. per cu. ft. depending on the gas velocity and particular particle size range selected.

Vaporous products of coking leave the bed 12 and pass overhead into inlet 26 of cyclone separator 28 arranged at the top interior of the reactor 10. The vaporous products contain entrained solids and the cyclone separator 28 or other gas-solids separating device is used to separate or recover the entrained solids and return them through dip leg 32 of the cyclone separator to the dense bed 12. More than one cyclone separator in stages may be used. The separated vapors pass overhead from the cyclone separator 28 through line 34 for further treatment in a recovery system.

Deposition of coke on the walls of the outlet line 34 and cyclone separator 28 has caused premature shutdowns of the coking unit. These coke deposits are believed to be formed through polymerization of unstable reaction products and have been shown to be greatly reduced and substantially eliminated by maintaining the effluent stream of vaporous products of coking at a high temperature, either substantially at the reactor temperature, or at a temperature which steadily increases from the reactor to the point of quenching. The natural tendency due to the endothermic reactions taking place is for the temperature to fall steadily as soon as the vaporous products of coking leave the dense bed 12. As the cooling takes place in the line 34 and cyclone separator 28, high boiling materials deposit on the walls and polymerization causes coke deposits.

Cooling of the vaporous reaction products and hence deposition of coke can be prevented according to this invention by introducing hot solid particles into the effluent stream from the reactor 10. The hot particles are preferably added at the inlet 26 to the cyclone separator and/or at one or more points along outlet line 34. This prevents coke deposition because of the introduction of large quantities of surface in the form of solid adsorbent materials. The most convenient source for the hot adsorbent coke solids is from the burner vessel 36 later to be described in greater detail. Ordinarily, coke particles of reasonably small particle size will contribute considerable surface, but this can be greatly enhanced by treating coke to be injected into the stream of vaporous overhead products of coking with steam at high temperatures. This has the effect of activating the coke particles and producing a porous structure through chemical reaction of the steam with the carbon.

Introduction of the hot adsorbent solids prevents or substantially reduces deposition of coke in the outlet line or lines and equipment associated with the reactor in that it heats the vaporous reaction products and prevents liquid separation due simply to condensation; any condensed liquid would go to coke because of the temperature. The introduced solid particles also have a scouring effect so that any coke which has been deposited previously can be removed. In addition the introduced adsorbent solid particles adsorb easily coked materials and prevent them from forming coke on equipment surfaces. The easily coked materials also tend to condense easily and by removing them from the vaporous reaction product effluent stream, they are prevented from fouling the apparatus. At least some of the adsorbent solids added to the inlet 26 of cyclone separator 28 and containing the easily coked materials as adsorbed materials are returned to the coking reactor 10 to further crack or coke these materials.

Hot coke particles from burner vessel 36 are passed through line 38 alone into the inlet line 26 of cyclone separator 28 or through line 38 and line 42 and/or line 44 to outlet line 34 from the cyclone separator 28. More or less points of addition of hot adsorbent solids may be used as found necessary.

The hot vaporous reaction products are passed through line 34 to a quench zone 46 which may be a separate

vessel or the bottom of a fractionating tower (not shown). The hot vaporous products have their temperature reduced to about 500° F. to 900° F. by the introduction of a quench medium through line 48. The quench medium may be any suitable liquid such as oil or water. Condensed liquid plus some scrubbed-out solids is withdrawn from the bottom of quench vessel 46 through line 52 and may be recycled to reactor 10 through feed line 18 or may be withdrawn from the process and discarded or disposed of in any desired manner. The reaction vapors leave the top of quench vessel 46 through line 54 and are preferably fractionated to recover chemical raw materials and/or motor fuel, gas oil cracking stock, a recycle oil fraction and gases. Instead of fractionating the vapors from line 54 they may be treated as desired to recover desired hydrocarbon fractions.

Returning now to the reactor 10, coke or coked particles are withdrawn downwardly from the dense bed 12 into stripping zone or vessel 56 which is shown as having a smaller diameter than reactor 10 and which depends from reactor 10. Steam or other suitable stripping gas is introduced through line or lines 58 into the bottom of stripping zone 56 to remove volatile hydrocarbons from the coke in the stripping zone and pass them into the dense fluidized bed 12 in reactor 10.

During the coking process, coke is formed so that some of the coke particles are preferably withdrawn from the bottom of the stripper 56 or through line 60 from line 62 leading from the bottom of stripper 56. The withdrawn coke particles are cooled and sent to storage or otherwise disposed of. Fluidizing gas may be introduced into line 62 through one or more lines 64. Line 62 is formed as a U-bend and the solids therein are maintained in a fluidized condition. A process showing the use of U-bends is described in Packie Patent No. 2,589,124, granted March 11, 1952. Gas such as steam or air in a small amount is added at the bottom of the U-bend 62 as at 66 to maintain fluidity of the solid particles. The upflow leg 67 of the U-bend is provided with a controllable restriction such as a valve or an orifice at 68 to assist in control of the circulation of solids and to provide a safety shut-off. The principal control, however, is usually effected by controlling the amount of gas introduced in the riser portion 67 of the U-bend system, through one or more ports 72. The greater the flow of gas to the riser, within limits, the greater the solids flow rate. Increasing the flow of gas decreases the density on this leg of the U-bend and therefore increases the pressure differential driving force. Other methods of controlling the circulation and transport of hot fluidized solids may be used. The upflow leg 67 empties into the bottom portion of the burner vessel 36 before referred to. Additional air is preferably introduced through line 74 and nozzles 76 into the lower portion of burner vessel 36 to burn coke from the solid particles and also to maintain the solid particles as a dense fluidized highly turbulent bed 78 having a level designated at 82 and a disperse or dilute phase 84 thereabove. Combustion gases leaving the disperse phase 84 contain entrained solids which are removed by passing the combustion gases through cyclone separator 86, the separated solids being returned to the dense bed 78 through dip leg 88 and the denuded combustion gases passing to the atmosphere through outlet line 92 or to additional separation devices and heat recovery systems if desired. Preferably 2 or 3 stages of cyclone separator are used on the burner side to remove solids from gases leaving through line 92.

During combustion of the coke particles in burner vessel 36, the particles are heated to a temperature higher than that in the reactor 10 so that when the particles are recirculated to the reactor they will contain sufficient heat to supply the heat of vaporization and cracking of the feed oil introduced into the reactor. The temperature in the burner vessel 36 will be about 50° to 500° F. higher than that in the reactor 10.

In the bottom of burner vessel 36 a well 94 is provided by short vertical partition 96 from which hot burned coke particles are removed through line 98 which may be provided with a fluidizing line or lines 102. One portion of the withdrawn hot coke or other solid particles is passed through a second U-bend 104 provided with an aerating or fluidizing line 106 at its lower portion and a control restriction 108 similar to restriction 68 above described. Upflow leg 112 of U-bend 104 communicates with reactor vessel 10 below the level 14 of the dense fluidized bed therein. Steam or other gas introduced through line 114 located above control restriction 108 controls the rate of flow of solids through U-bend 104 and to the reactor 10. The major portion of the hot coke particles from burner vessel 36 will pass through U-bend 104 and this may amount to about 75 to 99%, usually about 90 to 98% of the total withdrawn from burner 36 through line 98.

In addition to and shown as arranged above U-bend 104 is a third U-bend 116 which is also connected to burner withdrawal line 98 shown at a location above U-bend 104. The positioning and arrangement of U-bends 104 and 116 may be changed, if desired. U-bend 116 is also provided with an aeration line 118, control restriction 122 and gas inlet 124 for controlling the rate of flow of hot solids through U-bend 116 which are similar to the parts described in connection with U-bend 104. The upflow leg 126 of U-bend 116 is a line which provides hot solid particles to be supplied to the cyclone separator inlet 26 and outlet line above described. Line 126 forms a continuation of line 38 above described.

In cases where the hot coke particles or other inert solid particles being passed through line 38 alone or line 38 and/or line 42 and/or line 44 for preventing coke deposition in the outlet line and cyclone separator have a low surface area, the coke particles may have their surface area increased by passing them through a steam activation zone 128. Superheated steam is introduced into zone 128 through line 132 and gaseous reaction products are taken overhead through line 134. During activation the coke particles may be maintained as a dense fluidized bed. The temperature during activation is between about 1100° and 1600° F. with about 1200° to 1400° F. being preferred. The time of activation may vary between about 10 to 100 minutes. With this treatment coke particles having a surface area of about 1 to 10 square meters per gram may have their surface area raised to about 100 to 1000 square meters per gram. In some cases it may be desirable to obtain the high temperatures needed for this reactivation reaction by introducing some air with the steam or ahead of the steam, although less appreciation in surface area will result through the introduction of the air.

Line 136 is a by-pass for line 126 around the steam activation zone 128. Lines 42 and 44 lead off from line 38 but may lead off from line 136 where no steam activation is practiced.

In cases where more heat is required than is being produced by burner vessel 36 or where it is more desirable to withdraw product coke than burn it, oil or gas or other fuel may be introduced into vessel 36 through line 138.

In a specific example about 100 barrels per day of residual oil having an API gravity of 10° and a Conradson carbon of 18 and an initial boiling point of about 1150° F. and about 7000 lbs./day (or 20 wt. percent of feed) of steam were added to the reactor 10 at three longitudinally spaced points with most of the steam being added through lines 24. The oil feed was injected through nozzles into the fluid bed 12 in the reactor. The solids to feed oil ratio by weight to the reactor was about 15 to 1. The temperature in the reactor was 1000° F. and in the burner was 1150° F. About 2 to 3 gallons per hour of oil were injected into the burner 36 through line 138.

The circulating solid was coke having a particle size

of about 20-200 standard mesh with the majority of the particles being between about 48 and 80 mesh. The superficial velocity of the gas in the reactor 10 was about 1 ft./sec. at the bottom of the cylindrical portion and the density of the dense fluidized bed 12 was about 45 lbs./cu. ft. The superficial velocity of the gas in the burner 36 was about 3 ft./sec. and the density of the dense fluidized bed 78 was about 40 lbs./cu. ft.

The overhead products from line 34 were quenched 10 in quench zone 46 to a temperature of about 400° F. with a quench oil consisting of condensed liquid product boiling above about 100° F.

In the stripper 56 temperature was about 995° F. and the superficial velocity of the upflowing gas in the 15 stripper was about 1.0 ft./sec.

The yields obtained are as follows:

C ₃ , wt. percent	6.5
C ₄ , vol. percent	2.8
20 C ₅ , 430° F., vol. percent	15.0
430, 650° F., vol. per cent	10.7
650, 1050° F., vol. percent	30.0
1050° F. +, vol. percent	30.0
Coke, wt. percent	10.0

About 145 lbs. of coke per hour are withdrawn as product through line 60 and as losses through lines 52 and 92.

In the system shown on the drawing with only one cyclone separator 28 on the reactor size and in order to maintain the temperature from dropping in cyclone separator 28 and outlet line 34, about 20,000 to 40,000 lbs./day of coke from line 38 at a temperature of about 1100° F. would have to be introduced into cyclone separator 28. In order to obtain more nearly isothermal conditions it is desirable to distribute this coke among lines 38, 42 and 44. If this is not done, for simplicity, some additional coke should be added to line 38.

Operating the process as described above eliminates 40 coking problems heretofore encountered when cracking heavy residual oils.

What is claimed is:

1. A method of cracking oils which contain constituents unvaporizable at ordinary pressures without cracking which comprises contacting hydrocarbon oil with a dense fluidized highly turbulent bed of finely divided solids in a cracking zone maintained at a temperature above about 800° F. to produce lower boiling hydrocarbons while depositing coke on the solids, said cracking zone containing a disperse phase above the turbulent bed, removing coke-containing solids from said cracking zone and passing them to a separate combustion zone where oxygen-containing gas is introduced to burn the coke and heat the solid particles to a temperature above that existing in said cracking zone, separately recovering flue gas from said combustion zone, returning at least part of the hot solids from said separate combustion zone to the turbulent bed of said cracking zone to supply heat thereto, removing a stream of vaporous reaction products overhead from said cracking zone through a gas-solids separating stage, and introducing through an auxiliary injection means another portion of the hot solids as a discrete stream from said combustion zone into the stream of vaporous reaction products in the disperse phase passing 55 into said gas-solids separating stage to prevent deposition of coke from said vaporous reaction products.

2. A method according to claim 1 wherein the other portion of solid particles from said combustion zone to be passed to the vaporous reaction products stream is steam activated to increase their surface area before being introduced into the stream of vaporous reacting products passing overhead from said cracking zone.

3. A method of coking oils which contain constituents unvaporizable at ordinary pressures without cracking which comprises converting an oil in a dense fluidized

bed of finely divided solids in a lower portion of an enlarged zone provided with a gas-solids separation stage in the upper dispersed phase portion, said fluidized bed being maintained at a coking temperature, to produce lower boiling hydrocarbons while depositing coke on the solids, removing and passing solids from said dense bed to a separate combustion zone to burn coke and heat the solid particles to a temperature above said coking temperature, separately recovering flue gases from said sepa-

rate combustion zone, returning heated solids from said combustion zone to said dense fluid bed to supply heat thereto, and introducing another portion of heated solids as a discrete stream from said combustion zone into said gas-solids separation stage.
